UNITED STATES PATENT OFFICE.

J. ENSIGN FULLER, OF NEW YORK, N. Y., ASSIGNOR OF ONE-THIRD TO
GEORGE W. MUNRO, OF SAME PLACE.

PRIMARY BATTERY.

SPECIFICATION forming part of Letters Patent No. 600,850, dated March 15, 1898.

Application filed April 5, 1897. Serial No. 630,781. (No model.)

To all whom it may concern:

Be it known that I, J. ENSIGN FULLER, a citizen of the United States, residing at New York, in the county of New York and State 5 of New York, have invented certain new and useful Improvements in Primary Batteries, of which the following is a full and complete specification, such as will enable those skilled in the art to which it appertains to make and 10 use the same.

This invention relates to apparatus for generating electricity, and particularly to primary batteries; and the object thereof is to provide an improved device of this class which 15 is simple in construction and effective and durable in operation and which may be employed wherever such generators are applicable, and which is particularly adapted for use in connection with light machinery, incandescent or glow lamps, and for other and 20 similar purposes.

A further object of this invention is to provide an improved primary battery in which the life of the battery solution may be prolonged by separating the zincs from the solution when the battery is not in use and sealing the solution in separate cells by itself, so as to prevent said solution or the vapors therefrom from continuing to decompose the zincs, 25 the battery being inverted when the operation of separating the solution from the zincs is performed; and with these and other objects in view the invention consists in the construction, combination, and arrangement of parts 30 hereinafter described and claimed.

In the operation of strong-acid battery solutions the life of the solution may be prolonged by separating the zincs and the solution when the battery is not in use and sealing 35 the solution in cells by itself, so as to prevent said solution or the vapors therefrom from continuing to decompose the zincs, and also by such constant agitation as will continually change those portions of the solution 40 which come in contact with the poles of the battery when the latter is in use and by churning or agitating said solution thus retain the proper combination of the ingredients composing the same.

50 One of the chief objects of my invention consists in providing a mechanical device for

agitating or churning the solution and by means of which the hydrogen bubbles which adhere to and insulate the poles in batteries of this class as usually constructed are prevented from collecting on said poles, and the formation of what is called "chrome-alum" is also prevented.

It has been found that in bicycle and carriage lamps primary batteries capable of operating a small candle-power electric lamp will lose their power in two or three hours even though considerable agitation is brought about by the motion of the vehicle; but this motion, however, is not steady and is generally more in the nature of a tremor and does not churn or agitate the liquids or solution sufficiently; and one of the objects of this invention, therefore, is the production of batteries wherein the tendency of the battery solution to disintegrate under electric and chemical action is largely counteracted by means hereinafter described and wherein the properly-prepared exciting fluid is constantly presenting new contact portions to the surfaces 55 of the poles, thus obtaining the full electric discharge of which the battery is capable and a far greater number of "light-hours," and a further object of the invention being to provide a simple, cheap, and effective apparatus 60 which forms a part of the battery, by which all possible action of the solution is terminated by sealing the cells when not in use until the light or power is again required.

In lamps, such as bicycle and carriage 65 lamps, operated by electric-solution batteries it has been necessary to empty out the partly-used solution as soon as the destination is reached, no matter how short the ride, for the reason that although the acid solution may be 70 thrown away from the zincs by turning the battery upside down and actual contact with them terminated, still if the solution is left in the battery-cells the acid vapor rising from the solution will keep up the decomposition 75 of the zincs, so that such batteries have to be replenished completely before being used again, and in all primary-battery work no adequate provision has been made to completely seal the acid from the zincs and 80 preserve its strength.

The invention is particularly adapted for

use in connection with lamps for watchmen, carriages, bicycles, and similar vehicles; and said invention is fully disclosed in the following specification, of which the accompanying drawings form a part, in which the separate parts of my improvement are designated by the same letters of reference in each of the views, and in which—

Figure 1 is a perspective view of my improved battery when used as an electrical generator for an incandescent lamp, the battery being inverted; Fig. 2, a central longitudinal vertical section thereof; Fig. 3, a side elevation view of the device when used as a bicycle-lamp and showing its support; Fig. 4, an end view thereof; Fig. 5, a side view showing my improved battery connected with the frame of a bicycle and in operative connection with an incandescent or glow lamp, one of the springs shown in Figs. 3 and 4 being omitted; Fig. 6, a side view of the device when used as a carriage or buggy lamp and showing the supports therefor.

In recently-invented batteries, as well as in older styles, the cells have been made gas or vapor tight to keep the fluid from evaporating rapidly, and diminutive vents have been inserted or provided to prevent the accumulation of too great pressure; but these vents are necessarily not closed after the fluid and zincs are separated, because the chemical action is not stopped. Consequently the fluid goes on evaporating to the outside air and becomes weaker very fast.

In my improved battery the fluid is not only sealed away from the zincs when the battery is not in use, but the vent is contained in the closing-rod and sealing-stopper which I employ, and when the fluid is thrown into the storage-compartments, which form a part of the battery to separate it from the zincs, and the compartments are closed said compartments have no egress to the outer air, but are air-tight, while the moisture left clinging to the zincs in the working cells may be evaporated to the outer air and thus dry said zincs quickly.

In the construction of my improved battery I provide a casing A, which is composed of or molded from rubber or a composition of rubber and other suitable material, or aluminium coated with acid-proof and insulating enamel may be employed, and said casing is provided with vertical partitions a, formed integrally therewith, two of these partitions being shown in the drawings, the battery shown in the drawings being a three-cell battery. The three separate compartments formed by the vertical partitions a are divided centrally and transversely by partition-plates a², which are placed upon the corresponding ledges or shoulders formed in the inner end walls of the casing and on the partitions a, as shown at a³, and these partition-plates are preferably composed of the same material as the casing, and by means thereof

three separate storage-compartments a⁴ are formed and also three cells a⁵.

The partition-plates a² are intended to separate the cells a⁵ from the storage-compartments a⁴, and the partition-plates a project upwardly, preferably above the top of the sides of the casing, and the cells a⁵ are closed by caps a⁶, which are also secured on ledges or projections a⁷, formed on the inner walls of the casing and on the partition-plates. It is evident that this end of the battery may be closed in molding the casing A and the opposite end closed by caps, or similar caps may be used on the storage-compartment end of the cells also, instead of having that end as a part of casing A.

The positive poles of the battery are shown at B and are preferably tubular in form, and, as shown, are perforated or provided with slots b to permit of the free passage of the battery solution therethrough, and these slots or openings b are formed in the sides and upper ends of the carbons or poles B, or said positive poles may consist of separate parts, as will be readily understood.

Each of the caps a⁶ is provided with a central circular opening at a⁸, which is also arranged centrally of the tubular carbons B, and through said openings are passed the zincs D, which are cylindrical in form, and each of these zincs is provided with a screw-threaded bolt d, which is screwed thereinto and on which is mounted a rubber cylindrical packing d², and said bolt is provided with a milled head or nut C, in which is formed an annular groove C², and between the head C of each of said screw-threaded bolts and the rubber packing d² is placed a washer d³, which is preferably greater in diameter than the said head C and the opening a⁸ in the cap a⁶. My invention, however, is not limited to this exact form of construction for connecting the zincs D with the rod or bolt d and for closing the opening a⁸, and any suitable means may be provided for this purpose.

The cap or cover of the right-hand cell, as shown in Figs. 1 and 3, is provided with an angular spring-arm E, which is pivoted to said cap or cover and which is adapted to turn thereon and to engage with the groove C² in the milled head C of the zinc which passes into the right-hand cell, and said cap or cover is also provided with another spring-arm E², which is pivoted thereto and which is angular in form and which is adapted to engage with the groove C² in the milled head C of the bolt d, which passes into the zinc of the middle cell, and the cap or cover of the middle cell is provided with an angular spring-arm E³, which is pivoted thereto and which is adapted to engage with the annular groove C² in the milled head C of the bolt d, which passes into the zinc B of the left-hand cell.

The tubular carbons or poles B are connected with the caps a⁶ of their respective

cells by screws F, which are passed through said caps and into holes formed in the upper ends of said tubular carbons or poles, and said carbons or poles where the screws F enter are enlarged or thickened, as clearly shown in Fig. 2, and between the upper ends of said carbons or poles and said caps a⁶ are placed soft-rubber packing-rings a⁹, and by means of the screws F the carbons or poles B are drawn tightly against the caps a⁶ and the said rubber packing prevents the battery fluid or solution from coming in contact with said screws.

Connected with one of the screws by which the carbon or pole B of the left-hand cell is secured to the cap a⁶ is a wire or conductor f, which is connected with the screw-threaded socket of an incandescent electric light f², as shown in Fig. 1, or with a binding-post f³, as shown in Fig. 3, and the zinc of the first or left-hand cell is connected with the spring contact-arm E³ by means of the head C of the bolt d in said zinc, and said contact-arm is connected with one of the screws by which the carbon or positive pole of the middle battery is secured to the cap thereof by means of a wire f⁴, as shown in Fig. 1, and the zinc of the second or middle cell is electrically connected in the same manner with the carbon in the third or right-hand cell by the spring-arm E² and a wire f⁵, and the zinc of the third or right-hand cell is connected with the spring-arm E, with which is connected a wire f⁶, which is also connected with the head of the incandescent electric lamp f², as shown in Fig. 1, or with a binding-post f⁷, as shown in Fig. 3.

The casing A, as shown in Fig. 1, is provided with an ordinary reflector G, in which the incandescent lamp f² is placed, and in Figs. 3 and 4 I have shown two binding-posts f³ and f⁷, with which the wires f and f⁶ are connected, and these binding-posts may be used for any desired purpose.

The partition-plates a², which separate the compartments a⁴ from the cells a⁵, are secured in place in any desired manner, and each is provided with a central conical opening at g, the base of which is directed downwardly, and each of the cells is provided with a small curved vent-tube g², one end of which is passed through the corresponding plate a² and terminates at one side of the central conical opening g, and formed on or secured to the under side of each of the partition-plates a² is a screw-threaded hub or thimble g³, which projects into the corresponding compartment a⁴, and the bottom of each compartment is provided with a central opening g⁴, and passing through each of the openings g⁴ is a short shaft g⁵, the upper end of which is screw-threaded and adapted to enter the corresponding thimble or hub g³, and these shafts g⁵ are composed of rubber or similar material and each is provided at its upper end with a valve g⁶, which is adapted to close the opening g

the corresponding partition-plate a², and these valves g⁶ are held in place by tubular bolts g⁷, which are passed therethrough and into the shafts g⁵, and said shafts are each provided with a longitudinal passage g⁸, and mounted on or formed on the tubular bolts g⁷, between the valves g⁶ and the corresponding ends of the shafts g⁵, are washers g⁹, which are thickened at the center and the smaller portions of which bear upon the ends of the shafts g⁵.

The tubular bolts g⁷ are composed of hard rubber and provided at their ends with small heads H, and around the openings g⁴ in the casing through which the shafts g⁵ pass are formed or secured collars h, in which are placed packing-rings h², and these collars are closed by screw-threaded caps h⁴, through which the shafts g⁵ pass, and mounted on the end of each of said shafts is a gear-wheel h⁵, and the central shaft is projected and provided with a milled wheel h⁶, and by turning the milled wheel h⁶ each of the gear-wheels h⁵ will be operated. The longitudinal passages g⁸ in the shafts g⁵ are projected entirely through said shafts, and the ends of the shafts are provided with small cup-shaped cavities or inclosed recesses g⁹, one of which is shown in full lines in Fig. 2.

The shafts g⁵ in the compartments a⁴ are each screw-threaded, and the thread on the shafts in the outer compartments are the same and preferably left-hand threads, while the thread on the shaft in the inner compartment differs therefrom and is preferably a right-hand thread, and by turning the wheel h⁶ the openings g in the partition-plates a² may all be opened or closed at the same time, as will be readily understood, and at the same operation the ends of the vent-tubes g², which communicate with said openings, will also be opened or closed by said valves, and the ends of the vent-tubes g² project upwardly almost to the cap-plates a⁶ of the cells.

The upper ends of the shafts g⁵ are provided with grooves K, which extend through the screw-threaded portions thereof and which are shown in full lines in the left-hand compartment and in dotted lines in the other two compartments, and formed in the sides of the thimbles g³, near the top thereof, are vent openings or passages k, any desired number of which may be employed.

The passages g⁸ in the shafts g⁵ form vents to assist in the passage of the fluid to the working cells when the latter are filled from the storage-compartments, and the vent-tubes g² assist in the quick passage of the fluid from the working cells back into the compartments when it is desired to stop the working of the battery.

As will be readily understood, the normal position of the battery when not in use is that shown in Figs. 1 and 2, in which position the battery fluid is confined in the storage-compartments and sealed therein, and neither said fluid nor the fumes therefrom can come

in contact with the zincs D, and whenever it is desired to put the battery in operation it is inverted, and the wheel h⁶ is turned to the left, and this operation opens the ports or passages g in the partition-plates a², and the fluid passes into the cells, the battery being inverted for this purpose. In this position of the parts the passages g⁸ through the shafts G serve to allow the fumes arising from the battery fluid to escape, thus preventing the swelling or bursting of the battery-casing, and the object of the grooves K in the shafts G and the small ports or passages k in the thimbles g³ is to allow for the drainage of the battery fluid through said thimbles when the fluid is passing either into the cells a⁵ or to the compartments a⁴, and it will be understood that the proper position of the battery when in operation is that shown in Figs. 3 and 4.

It will also be understood that my invention is not limited to the material of which the various parts of the battery herein shown and described are composed, and the best material for this purpose may be selected.

In practice the heads C of the bolts d are screwed down, so that the washers d³ press firmly upon the cap-plates a⁶, and in this operation the soft-rubber packing d² is compressed, so as to tightly close the openings a⁸ in the cap-plates, and the washers d³ rest on said cap-plates, and it will also be apparent that other means may be provided for opening and closing the ports or passages formed in the partition-plates a² at the same time, and I do not claim this as new, and an ordinary stuffing-box arrangement may be used.

In practice the battery fluid is provided or furnished in bottles or receptacles which are marked off on the label, showing just how much to put in each cell, and the stoppers or cell-closers, which consist of the valves g⁶, being pressed into the openings in the partition-plates the fluid is poured in through the central openings a⁸ in the cap-plates, and the zincs D are then placed in position, the knobs C are turned to the right, and cells a⁵ are firmly sealed, so that no liquid or vapor can escape through openings a⁸ when the battery is in the position shown in Figs. 3 and 4 and in operation, it being understood that by turning the movable knobs C on the bolts or screws d to the left the rubber packings d² will contract, so that the zincs may be drawn out, and in this operation the spring-arms E, E², and E³ must be turned, so that they will not engage with the knobs or heads C of said bolts, and said spring-arms may be turned back again into position after the zincs have been secured in place, as described.

When the cell is in the position shown in Figs. 3 and 4 and the battery is in operation, the shafts g⁵ may be operated or turned so as to slightly open the ports or passages g in the partition-plates a²; but this is not essential to the operation of the battery, and whenever it is desired to stop the operation of the bat-

tery said battery is inverted and the shafts g⁵ are turned, so that the battery fluid will flow out of the cells into the storage-compartments a⁴, as hereinbefore described, and it will thus be seen that when the battery is not in use the battery fluid does not come in contact with the zincs and there is no waste or consumption of the latter.

It will be apparent that my improved battery may be used whenever such devices are applicable; but in Figs. 3 to 5, inclusive, I have shown the method of applying my improved battery to a bicycle or similar vehicle for the purpose of operating an incandescent or glow lamp, and in this application of my improvement I provide means for agitating or shaking the battery and the battery fluid when the battery is in operation, the object of this construction being hereinbefore set out. For this purpose I secure to the sides of the casing A of the battery pivoted arms M, to which are attached spiral springs m, and secured to the upper ends of these springs is a cross-plate m², centrally of which is secured a supplemental spiral spring m³, and to the spring m³ is secured a cross-bar m⁴, which is provided on its upper surface with a longitudinal groove m⁵, and the cross-bar m⁴ is provided with transverse slots or openings m⁶, through which are passed straps m⁷, by means of which the battery may be connected with the upper horizontal rod m⁸ of a bicycle-frame.

The binding-posts f³ and f⁷ serve as attachments for wires or conductors O, and connected with the upper part of the forward portion of the frame of the bicycle is a clamp O², which is provided with an arm O³, to which is secured in any desired manner a reflector O⁴, in which is placed an ordinary incandescent or glow lamp, which is not shown, and said reflector O⁴ may be provided with a backwardly-directed tubular attachment O⁵, in which may be placed a glass, by means of which the light may be seen from the rear of the vehicle.

In the construction shown in Fig. 5 the spring m³ is omitted; but the operation will be substantially the same in both cases, and by means of the spring m² and the spring m³, when the latter is employed, the battery will be kept in a constant state of agitation, as will also the battery fluid therein, and the life of said battery may thus be prolonged, as hereinbefore described, and other forms of springs may be employed. I have also shown in Fig. 6 devices for supporting my improved battery on a carriage or other vehicle, and these devices consist of a brace or other suitable support R, on which is mounted a spiral spring R², on which is placed a frame R³, by means of which the battery may be supported, and by reason of the spring R² the battery will be constantly agitated or shaken when the vehicle is in motion, and this agitating or shaking of the battery will result in agitating or shaking the battery fluid, as will be readily understood, and the result of this

operation will be the same as that hereinbefore described with reference to the construction shown in Figs. 3 to 5, inclusive.

My improvement is not limited to the exact form, construction, and arrangement of the various parts thereof as herein shown and described, and it will be apparent that changes therein and modifications thereof may be made without departing from the spirit of my invention or sacrificing its advantages.

Having fully described my invention, I claim as new and desire to secure by Letters Patent—

1. In a primary battery, a casing provided with vertical partitions, and transverse partition-plates, whereby separate cells and storage-compartments are formed, said cells being closed at one end by said partition-plates, and at the other by cap-plates to which depending, tubular, positive poles are secured and which are removable therewith, said cap-plates being also provided with central openings through which the zincs are passed, and said partition-plates being also provided with ports or passages whereby the battery fluid may be passed from the cells to the compartments, and from the compartments back to the cells, and means for closing or opening said ports or passages consisting of shafts 30 which pass through the bottoms of said compartments, substantially as shown and described.

2. In a primary battery, a casing provided with vertical partitions, and transverse partition-plates, whereby separate cells and storage-compartments are formed, said cells being closed at one end by said partition-plates, and at the other by plates, to which depending positive poles are secured, said plates being also provided with central openings through which the zincs are passed, and said partition-plates being also provided with ports or passages whereby the battery fluid may be passed from the cells to the compartments, and from the compartments back to the cells, and means for closing or opening said ports or passages simultaneously, consisting of shafts which pass through the bottoms of said compartments and are geared in connection substantially as shown and described.

3. A battery comprising a casing which is provided with vertical partitions whereby separate chambers are formed therein, said chambers being divided by transverse partition-plates whereby separate cells and storage-compartments are formed, said cells being closed at one end by said transverse partition-plates, and at the other by plates to which carbons or poles are secured, said carbons being provided with side openings, and also with central openings through which are passed the zincs, and said transverse partition-plates being provided with ports or passages, and means for opening and closing the same consisting of shafts which pass through the bottoms of said compartments and are

provided with valves at their inner ends, substantially as shown and described.

4. A battery comprising a casing which is provided with vertical partitions whereby separate chambers are formed therein, said chambers being divided by transverse partition-plates whereby separate cells and storage-compartments are formed, said cells being closed at one end by said transverse partition-plates, and at the other by cap-plates, tubular carbons or poles secured to the bottoms of said cap-plates, and provided with side openings, and said cap-plates being provided with central openings through which are passed the zincs, and said transverse partition-plates being provided with ports or passages, and means for opening and closing the same consisting of shafts which pass through the bottoms of said compartments, said zincs being provided with screw-threaded bolts which are passed therein, and on which are mounted rubber packings, and said bolts being provided with washers which are adapted to bear on said cap-plates, and with circular heads, substantially as shown and described.

5. A battery comprising a casing which is provided with vertical partitions whereby separate chambers are formed therein, said chambers being divided by transverse partition-plates whereby separate cells and storage-compartments are formed, said cells being closed at one end by said transverse partition-plates, and at the other by cap-plates, tubular carbons or poles secured to the bottoms of said cap-plates, and provided with side openings, and said cap-plates being provided with central openings through which are passed the zincs, and said transverse partition-plates being provided with ports or passages, and means for opening and closing the same from outside of the casing, said zincs being provided with screw-threaded bolts which are passed therein, and on which are mounted rubber packings, and said bolts being provided with washers which are adapted to bear on said cap-plates, and with circular heads, and said circular heads being provided with annular grooves, and said cap-plates with a plurality of spring-arms which are equal in number said zincs, and which are adapted to operate in connection with said grooves, substantially as shown and described.

6. A battery comprising a casing which is provided with vertical partitions whereby separate chambers are formed, said chambers being provided centrally with transverse partition-plates, whereby cells and compartments are formed, and said cells being provided with cap-plates, tubular carbons or poles secured to said cap-plates and provided with side openings, zincs which are passed through central openings formed in said cap-plates, and which are supported by bolts on which are mounted packings which are adapted to close said openings in said cap-plates,

and said transverse partition-plates by which the cells and storage-compartments are formed, being provided with central ports or passages, and devices for closing or opening the same simultaneously, consisting of shafts which pass through the casing, substantially as shown and described.

7. A battery comprising a casing which is provided with vertical partitions whereby separate chambers are formed, said chambers being provided centrally with transverse partition-plates, whereby cells and compartments are formed, and said cells being provided with cap-plates, carbons or poles secured to said cap-plates, zines which are passed through central openings formed in said cap-plates, and to which are attached suitable packings which are adapted to firmly close said openings in said cap-plates, and said transverse partition-plates by which the cells and storage-compartments are formed, being provided with central ports or passages, and devices for closing or opening the same simultaneously, consisting of shafts which pass through the bottom of the casing, and are screw-threaded, and are adapted to enter screw-threaded thimbles formed on or secured to the bottoms of said transverse partition-plates, and valves connected with the inner ends of said shafts, substantially as shown and described.

8. A battery comprising a casing which is provided with vertical partitions whereby separate chambers are formed, said chambers being provided centrally with transverse partition-plates, whereby cells and compartments are formed, and said cells being provided with cap-plates, carbons or poles secured to said cap-plates, zines which are passed through central openings formed in said cap-plates, and attached to which are packings which are adapted to firmly close said openings in said cap-plates, and said transverse partition-plates by which the cells and storage-compartments are formed, being provided with ports or passages, and devices for closing or opening the same, consisting of shafts which pass through the bottom of the compartments, and are screw-threaded, and are adapted to enter screw-threaded thimbles formed on or secured to the bottoms of said transverse partition-plates, and valves connected with the inner ends of said shafts, and said cells being provided with vent-tubes which extend into said transverse partition-plates, and which open into the ports or passages formed therein, substantially as shown and described.

9. A battery comprising a casing which is provided with vertical partitions whereby separate chambers are formed, said chambers being provided centrally with transverse partition-plates, whereby cells and compartments are formed, and said cells being provided with cap-plates, tubular carbons or poles secured to said cap-plates, and provided with

side openings, zines which are passed through central openings formed in said cap-plates, and which are supported by bolts on which are mounted packings which are adapted to close said openings in said cap-plates, and said transverse partition-plates by which the cells and storage-compartments are formed, being provided with central ports or passages, and devices for closing or opening the same simultaneously, consisting of shafts which pass through the bottom of the casing, and are screw-threaded, and are adapted to enter screw-threaded thimbles formed on or secured to the bottoms of said transverse partition-plates, and valves connected with the inner ends of said shafts, and said cells being provided with vent-tubes which extend into said transverse partitions, and which open into the ports or passages formed therein, and said shafts and the valves by which the ports or passages, in the transverse partition-plates are closed, being also provided each with a longitudinal vent or passage, substantially as shown and described.

10. The herein-described battery, comprising a casing provided with separate cells and separate storage-compartments, said cells and storage-compartments being separated by transverse partition-plates which are provided with ports or passages, devices for opening and closing said ports or passages, said cells being also provided each with a cap-plate to which the poles are secured, and with vent-tubes which communicate with the ports or passages in the transverse partition-plates, substantially as shown and described.

11. A battery comprising a casing which is provided with partitions whereby separate chambers are formed, a transverse partition-plate mounted in each of said chambers whereby separate cells and storage-compartments are formed, said partition-plates being also provided with a port or passage, and said compartments with shafts which pass therethrough, and are provided with valves which are adapted to open and close said ports or passages, and said cells being each provided with vent-tubes which communicate with said ports or passages, substantially as shown and described.

12. A battery comprising a casing which is provided with partitions whereby separate chambers are formed, a transverse partition-plate mounted in each of said chambers whereby separate cells and storage-compartments are formed, said transverse partition-plates being also provided with ports or passages, and said compartments with shafts which pass therethrough, and are provided with valves which are adapted to open and close said ports or passages, and said cells being each provided with vent-tubes which communicate with said ports or passages, and cap-plates to which the poles of each cell are secured, substantially as shown and described.

13. A battery constructed as herein de-

scribed and provided with vertical partition-
plates whereby separate chambers are formed,
and transverse partition-plates whereby said
chambers are divided into cells and storage-
compartments, said cells being provided with
closing-plates through which openings are
formed, positive poles or carbons secured to
said closing-plates, and zincs which are passed
through said openings, and said partition-
plates being provided with ports or passages
and shafts which pass through said compart-
ments and by which said ports or passages
may be closed or opened, substantially as
shown and described.

14. A battery constructed as herein de-
scribed and provided with vertical partition-
plates whereby separate chambers are formed,
and transverse partition-plates whereby said
chambers are divided into cells and storage-
compartments, said cells being provided with
closing-plates through which openings are
formed, positive poles or carbons secured to
said closing-plates, and zincs which are passed
through said openings, and said partition-
plates being provided with ports or passages
and shafts which are passed through said com-
partments, and are provided with valves at
their inner ends, said shafts being adapted
to be operated simultaneously, substantially
as shown and described.

15. A battery constructed as herein de-
scribed and provided with vertical partition-
plates whereby separate chambers are formed,
and transverse partition-plates whereby said
chambers are divided into cells and storage-
compartments, said cells being provided with
closing-plates through which openings are
formed, positive poles or carbons secured to
said closing-plates, and zincs which are passed
through said openings, and said partition-
plates being provided with ports or passages
and shafts which are passed through said com-
partments, and are provided with valves at
their inner ends, said shafts being adapted
to be operated simultaneously, substantially
as shown and described.

16. A battery constructed as herein de-
scribed and provided with vertical partition-
plates whereby separate chambers are formed,
and transverse partition-plates whereby said
chambers are divided into cells and storage-compartments, said cells being provided with closing-plates through which openings are formed, positive poles or carbons secured to said closing-plates, and zincs which are passed through said openings, and said transverse partition-plates being provided with ports or passages and shafts which are passed through said compartments, and are provided with valves at their inner ends, said shafts and valves being provided with longitudinal vents which extend therethrough and said cells being also provided with vent-tubes which communicate with the ports or passages in said partition-plates, and which are adapted to be closed by said valves, substantially as shown and described.

17. A battery consisting of a casing pro-
vided with vertical partition-plates, and cen-
tral transverse partition-plates, whereby cells
and compartments are formed, said cells be-
ing provided with carbons and detachable
zincs, and said transverse partition-plates be-
ing provided with ports or passages, and
means for closing said ports or passages, con-
sisting of shafts which pass through said cas-
ing, and which are adapted to be operated
from the outside of the casing, said shafts be-
ing provided with valves at their inner ends,
and being geared in connection at their outer
ends, substantially as shown and described.

In testimony that I claim the foregoing as
my invention I have signed my name, in pres-
ence of the subscribing witnesses, this 2d day

of April, 1897.

J. ENSIGN FULLER.
